Primary Examiner — Amber R Stiles*Assistant Examiner* — Molly K. Orzechowski(74) Attorney, Agent, or Firm — Greer, Burns & Crain, Ltd(57) CLAIM

The ornamental design for a footwear upper as shown and described.

DESCRIPTION

FIG. 1 is a front perspective view of a footwear upper showing my new design;

FIG. 2 is a side elevational view thereof;

FIG. 3 is an opposite side elevational view thereof;

FIG. 4 is a top plan view thereof;

FIG. 5 is a bottom plan view thereof;

FIG. 6 is a rear elevational view thereof; and,

FIG. 7 is a front elevational view thereof.

The broken lines in FIGS. 1–7 represent portions of the footwear that form no part of the claimed design. The dashed lines which define the bounds of the claimed design form no part thereof.

1 Claim, 3 Drawing Sheets(56)
